UNITED STATES PATENT OFFICE.

MARTIN W. TUBBS, OF PORTVILLE, NEW YORK.

REVOLVING BLACKBOARD.

SPECIFICATION forming part of Letters Patent No. 625,615, dated May 23, 1899.

Application filed February 25, 1898. Serial No. 671,589. (No model.)

To all whom it may concern:

Be it known that I, MARTIN W. TUBBS, of Portville, in the county of Cattaraugus and State of New York, have invented a new and 5 Improved Revolving Blackboard, of which the following is a full, clear, and exact description.

The invention relates to educational appliances; and its object is to provide a new and 10 improved revolving blackboard arranged to carry a plurality of flexible blackboards normally wound on rollers, but adapted to be singly unwound and extended over and fastened to a fixed support and used similarly 15 to an ordinary blackboard, the whole arrangement being simple and durable in construction, very compact, and requiring wall-space for one blackboard only, with the advantage of having the use of several, also permitting 20 of concealing or exposing work on the flexible blackboard at the pleasure of the teacher.

The invention consists of novel features and 25 parts and combinations of the same, as will be described hereinafter and then pointed out in the claims.

Reference is to be had to the accompanying drawings, forming a part of this specification, in which similar characters of reference indicate corresponding parts in all the figures.

30 Figure 1 is a front elevation of the improvement. Fig. 2 is an end elevation of the same. Fig. 3 is a sectional front elevation of the same on the line 3-3 in Fig. 2. Fig. 4 is a cross-section of one of the spools for carrying a 35 flexible blackboard, and Fig. 5 is a reduced end elevation of a modified form of the improvement.

The improved revolving blackboard is mounted on a support A, provided at its upper end with eyes A', adapted to engage hooks B', secured to a wall B or other base. On the support A are secured brackets A², formed at their forward ends and on the top with square notches A³ for receiving the correspondingly-shaped ends C' of a shaft C, held against rotation by its square ends C' fitting into said notches, but adapted to be removed from the brackets by lifting the shaft ends out of the notches. On the round portion of the shaft 45 C, between the brackets A², are mounted to

revolve the heads D, rigidly connected with each other by a hub D', so that the said heads rotate in unison, but are normally held in position by a spring E, coiled on the shaft C and fastened at one end thereto, the other end of 55 the spring being secured to the hub D', as is plainly indicated in Fig. 3.

In each square end C' of the shaft C is formed a recess C², adapted to be engaged by a pin F', held on an arm F, fitted to the head D, so as to lock the latter against rotation unless the two arms F are swung outward to carry their pins F' out of engagement with the recesses C² in the shaft C. The heads D are provided with arms D², preferably four 65 in number, each formed with a square recess D³ for receiving the square end G' of a shaft G. On each of the shafts G is mounted to 70 rotate loosely a spool H, on which is adapted to wind a flexible blackboard I, arranged to 75 unwind to extend the flexible blackboard over an inclined or perpendicular board J, attached at the top to the support A and supported from the wall B, as indicated in Figs. 1 and 2. Each flexible blackboard I is provided at its outer free end with a hem containing a metal rod I², projecting to form a stop on the head D, and a loop I' for pulling the blackboard into an extended position over the board J and for fastening the blackboard 80 in position thereon by engaging the loop with a fixed pin J' on the board J. Each of the spools H is pressed on by a spring E', similar to the spring E and coiled on the shaft G, one end of said spring being secured to the shaft 85 and the other end to the spool, as will be readily understood by reference to Fig. 3. Now when the spool H is in a lowermost position and the operator pulls on the loop I' then the said spool is rotated against the tension of the spring E', and the flexible blackboard I is unwound and passed over the support J and fastened thereto, as previously explained. When the blackboard is in this 90 position, the teacher or pupil can readily 95 write on the extended face of this board, and when it is desired to use another flexible blackboard and to conceal the writing on the one already used then the operator disconnects the loop I' from the pin J', and the spring 100

E' now rotates the spool H in an opposite direction to wind up the flexible blackboard I'.

The spool H is normally locked against rotation on the shaft G, and for this purpose I

5 provide arms K, pivoted on the spools and provided with pins K', adapted to engage recesses G² in the corresponding end G' of the shaft G. When it is desired to unwind the flexible blackboard I, as described, or to again 10 wind it upon the roller, the arm K is thrown out of engagement with the end G' of the shaft G to allow rotation of the spool, as before mentioned. (See Fig. 4.)

In order to hold the shafts G securely in 15 place in their bearings in the arms D², I provide each of the arms with a pivoted arm L, adapted to swing in contact with a face of the square end G' of the shaft in the upper portion of the notch D³, and the free end of the 20 arm L is engaged by a spring-catch L', pivoted to the arm D², to lock the other arm L in place over the square end G' of the shaft G to hold the same in place on the head D.

When it is desired to remove the shaft G 25 and the spool carried thereby, together with the flexible blackboard on the spool, then the operator releases the catch L' from the arm L and swings the latter inward to free the square end G' of the shaft. The shaft can now be 30 lifted out of the notches D³ and another shaft, with spool and blackboard, can be placed in position on the heads.

When it is desired to unwind any one of the 35 flexible blackboards I, it is first necessary for the operator to unlock the heads by throwing the arms F out of engagement with the square ends C' of the shaft C, and then rotate the heads on the shaft C until the spool, with the desired flexible blackboard I, is in a lower- 40 most position. This blackboard is now unwound and passed over the support J and locked thereto, as before explained. Now it is evident that when the heads D are rotated, as described, the spring E is wound up, so as 45 to exert a tension against the heads to hold the extended blackboard I in a stretched position on the support J. By the arrangement mentioned the blackboard is not wrinkled, and consequently permits of properly writing, 50 any desired matter thereon. The written matter may be washed off the blackboard after each lesson, or the matter may be allowed to remain on the blackboard and the latter returned or wound up on its spool to conceal the 55 writing and preserve the same for future use.

In the arrangement shown in Fig. 5 the drawn-out flexible blackboard I³ is held against the vertically-disposed support J' by means of a frame R, pivoted on the brackets 60 A⁶ and pressed rearwardly by springs R' to clamp the upper portion of the blackboard I³ against the upper part of the support J² to cause the flexible blackboard I³ to hang properly in a vertical position over the said support J'. The frame R can be swung upward 65 out of the way of the unwound flexible black-

board (see dotted lines, Fig. 5) to permit of manipulating the revolving blackboard as above described and for the purpose mentioned.

Having thus fully described my invention, I claim as new and desire to secure by Letters Patent—

1. A blackboard, provided with a spring-pressed frame adapted to engage a flexible 75 blackboard, to press the same against a support and hold the blackboard in position on the support, substantially as shown and described.

2. A revolving blackboard, comprising connected heads mounted to turn, a torsion-spring connected with the said heads, a plurality of spring-actuated spools mounted to turn on the said heads, flexible blackboards adapted to wind on the said spools, and means 85 for locking the said spools against rotation, substantially as shown and described.

3. A revolving blackboard, comprising brackets, a central shaft carried by said brackets, connected spring-actuated heads mounted to turn on said shaft, a plurality of shafts carried by said heads, spring-actuated spools carried by said shafts, and a flexible blackboard for each spool, and adapted to wind on and unwind from the spools, substantially as 95 shown and described.

4. A revolving blackboard, comprising brackets, a central shaft carried by said brackets, connected spring-actuated heads mounted to turn on said shaft, a plurality of shafts 100 carried by said heads, spring-actuated spools carried by said shafts, a flexible blackboard for each spool, and adapted to wind on and unwind from the spools, and means for locking said shafts against rotation, substantially 105 as shown and described.

5. A revolving blackboard, provided with connected heads having square slots, shafts having square ends fitting into said slots, arms pivoted to the heads and engaging the 110 shaft ends and holding the latter in place in the head-slots, and spring-catches for engaging the arms and holding the same in place, substantially as shown and described.

6. A revolving blackboard, comprising connected heads mounted to turn, a torsion-spring connected with the said heads, a plurality of spring-actuated spools mounted to turn on the said heads, flexible blackboards adapted to wind on the said spools, a fixed 120 support for an extended flexible blackboard to rest on, and a spring-pressed frame engaging the extended blackboard to hold against the said support, with or without the revolving device, substantially as shown and described.

7. In a revolving blackboard, the combination with a support having angular notches, of a shaft having its ends shaped to fit in the notches of the support and provided with a recess, a drum or spool fitted to revolve on the shaft, and an arm pivoted to the drum or

spool and provided with a pin for engaging the recess of the shaft, substantially as described.

8. In a revolving blackboard, the combination with a support, a revolving spool, and a flexible blackboard wound on said spool, of a pivoted and spring-pressed frame for clamp-

ing the blackboard against the support, substantially as described.
